UNITED STATES PATENT OFFICE

WILLIAM H. CLAYTON, OF FORT WORTH, TEXAS

ICE-SERVING CONVEYER

Application filed May 10, 1927. Serial No. 190,228.

My invention relates to ice carrying conveyers and more particularly to conveyers for retail service; and the object is to provide a simple apparatus which is readily installed at small expense and which is easily operated and by which much time is saved in operation and much expense avoided in delivering ice. Another advantage is that the work of delivering the ice is made less hazardous to the operators and customers can be served in much shorter time. Other objects and advantages will be fully explained in the following description and the invention will be more particularly pointed out in the claims.

Reference is had to the accompanying drawings which form a part of this application.

Fig. 1 is a side elevation of the conveying apparatus, the machine frame being shown resting on the floor line of the building.

Fig. 2 is a plan view of the same.

Fig. 3 is a broken perspective view of the conveying apparatus.

Fig. 4 is a rear elevation, the angle iron supporting bars being shown in section.

Fig. 5 is an enlarged broken view of the conveyer, illustrating the mechanism for taking up the slack.

Similar characters of reference are used to indicate the same parts throughout the several views.

Conveyer chains 1 and 3 are provided for moving the ice blocks. Cleats 4 are provided and attached to the chains 1 and 3 to force the blocks along slideways provided by angle-bars 6, of which the horizontally disposed flanges constitute spaced supporting slide members for supporting the ice, while the vertically disposed flanges constitute longitudinal guide means for maintaining the ice on its slideway to be moved by the cleats 4, which also separate the ice blocks and prevent their freezing together, and which are suitably supported, preferably by means of the horizontal flanges of the angle-bars 6. Thus the ice blocks are prevented from freezing together and positive delivery thereof is assured as they are forced along the slides by the cleats 4, which will break loose any

blocks which may freeze to the slides. The chain 3 is driven by wheel 12 which is rigid with hollow shaft 35. The chain 1 is driven by wheel 2 which is rigid with a hollow shaft 16. The hollow shafts 16 and 35 are mounted on a shaft 5 which serves as a bearing for these hollow shafts. The shaft 5 is supported in bearings 42 which are adjustably attached to bars 44 which are attached to the uprights 18. At the front end of the machine, an idle sprocket wheel 40 supports the chain 3 and an idle sprocket wheel 39 supports the chain 1. The wheels 39 and 40 are supported on a shaft 38 which is mounted in uprights 41. The uprights 41 are attached to the base members 17. Other upright supports 18 and 43 are attached to the base members 17. Cross bars 37 are attached to the uprights 18 and 43 for supporting the angle bars 6. The blocks of ice are slid along on the angle bars 6 towards a chute 21 to be delivered thereby to the purchasers. For taking up the slack in the chains 1 and 3, the bearings 42 are made adjustable on the supporting bars 44. The bearings 42 have base members 45 which are dovetailed into the supporting bars 44. Screw threaded shafts or rods 46 have swivel connections with the base members 45 and operate through nuts 47 which are attached to uprights 18.

The chains 1 and 3 may be driven by any suitable power, either manual power or motor power. Means for actuating the wheels 2 and 12 manually are illustrated in the drawings. A disk or crank disk 7 is rigid with the hollow shaft 16 and provided with a plurality of shoulders or abutments 10. A lever 8 is loosely mounted on the hollow shaft 16 and provided with a spring-actuated dog 9 slidably mounted in bearings 25 attached to the side of the lever 8 and adapted to engage the abutments 10. The wheels or disks 7 and 11 may be more appropriately called ratchet wheels. The spring on the dog 9 holds the dog yieldingly against the ratchet wheel for propelling the wheel or disk. An upward pull on the lever 8 will cause the dog to turn the ratchet by lifting up an abutment or tooth 10 to move the chain a limited distance. When the power is released, the

weight of the lever 8 will cause the lever 8 to drop back to starting position without moving the ratchet wheel, the weight of the undelivered blocks of ice being sufficient to prevent backward movement of the ratchet wheel. This movement of the ratchet wheel must be so timed as to move one block of ice at a time to be delivered to the chute 21.

In a similar manner, a ratchet wheel 11 is rigid with the hollow shaft 35 and is provided with an operating dog 9, an operating lever 13, and teeth 10 for driving the chain. The lever 11 operates in the same manner as lever 8.

A cord 26 is attached to the lever 8 and run over a pulley 27 and then over another pulley or idler 28 and thence to a convenient location for the operator. In the same manner a cord 29 is attached to lever 13 and then run over idlers 30 and 31 to a convenient location for the operator. Each chain 1 and 3 can be loaded with a plurality of blocks of ice so that the operator has simply to pull the proper cord to get a block of ice of the required weight. The ice may be delivered through a door 32 in the wall 33 of a building. The lower members of the angle bars 6 are cut away at 48 for the passage of the cleats 4.

The machine herein shown is portable so that it can be located at any convenient place. The longitudinal base members 17 are made rigid with each other by cross braces 49 and the machine frame is made rigid by the uprights 18 and 43 and the cross bars 37 and the longitudinal angle bars 6.

Various changes in the sizes, proportions, construction and arrangement of the several parts of the machine may be made without departing from my invention.

What I claim is,—

1. An ice serving conveyer comprising an upright frame, sprocket wheels provided with shafts journaled in said frame, a chain running on said sprocket wheels, means attached to said frame on both sides of the upper part of said chain and constituting slides for blocks of ice, cleats attached to said chain for propelling the blocks of ice along said slides, and means for driving one of said sprocket wheels consisting of a ratchet wheel rigid with the sprocket wheel to be driven, a lever loosely mounted on the shaft of the sprocket wheel to be driven, a spring-actuated dog carried by said lever adapted to engage the teeth of said ratchet wheel, and means for actuating said lever.

2. An ice serving machine comprising a frame, two pairs of angle bars mounted on said frame, each pair having their horizontal flanges adjacent to each other, sprocket wheels provided with shafts journaled in said frame, sprocket chains driven by said sprocket wheels and running between said flanges, said flanges constituting slides for ice blocks, cleats at-

tached to said chains and projecting over said flanges for moving blocks of ice, and means for driving each sprocket chain.

3. An ice serving machine comprising an upright frame and pairs of angle bars attached to and constituting the top of said frame, each pair of angle bars having their horizontal flanges projecting towards each other, rear and front shafts journaled in said frame, sprocket wheels mounted loosely on one of said shafts, sprocket wheels provided with hollow shafts rigid therewith and journaled on the other of said shafts, sprocket chains running on said sprocket wheels between said angle bars, cleats attached to said sprocket chains and projecting over said flanges for moving blocks of ice, and selective means for driving each sprocket chain.

4. In an ice serving machine to be located inside an ice storage chamber and operated from the exterior of said chamber to successively deliver blocks of ice to the exterior of said chamber through an opening in the chamber wall, a frame, an endless chain supported on sprockets and running longitudinally of said frame and provided with spaced laterally extended cleats spaced supporting slide members carried by said frame at either side of said chain underlying said laterally extended portions of said cleats for supporting said cleats and for supporting blocks of ice interposed between said cleats to be maintained separate thereby, a chute for receiving blocks of ice delivered at one end of said supporting slide members for conducting them through said wall opening, and means operable from the exterior of said chamber for intermittently advancing said chain to intermittently slide said blocks of ice along said members toward said chute for delivery thereto comprising a ratchet wheel coupled to drive one of said sprockets, a dog engageable with said ratchet wheel to rotate the same and means for intermittently engaging and moving said dog to move said ratchet wheel; whereby freezing together of said blocks is avoided, and positive delivery thereof is assured.

5. In an ice serving machine to be located inside an ice storage chamber and operated from the exterior of said chamber to successively deliver blocks of ice to the exterior of said chamber through an opening in the chamber wall, a frame, a slideway carried by said frame comprising longitudinal ice supporting slide members for slidely supporting blocks of ice positioned thereon, a chain running longitudinally of said frame and provided with upstanding spaced cleats extending above said ice supporting slide members to lie between and maintain separate blocks of ice positioned thereon, a chute for receiving blocks of ice delivered at one end of said supporting slide members for conducting them through said wall opening, and

means actuatable from the exterior of said chamber operable to advance said chain a limited distance to intermittently slide said blocks of ice along said members toward said chute for successive delivery thereto; whereby freezing together of said blocks is avoided, and positive delivery thereof is assured.

5 In testimony whereof, I set my hand, this 5th day of May, 1927.
